UNITED STATES PATENT OFFICE.

EMILE GAUDION, OF MAROLLES, FRANCE.

MACHINE FOR THE MANUFACTURE OF BUTTONS.

1,072,221.

Specification of Letters Patent.

Patented Sept. 2, 1913.

Application filed February 6, 1912. Serial No. 675,881.

To all whom it may concern:

Be it known that I, EMILE GAUDION, a citizen of the Republic of France, residing at Marolles, Oise, in the Republic of France, 5 manufacturer, have invented certain new and useful Improvements in Machines for the Manufacture of Buttons, of which the following is a specification.

This invention relates to improvements in 10 machines for the manufacture of buttons turned in corozo, bone and other materials, and particularly to machines or lathes in which the plate to be worked to make a button is held sustained during the work 15 against a non rotary claw located in front of the rotary cutting tool.

In the greater number of machines, the 20 plate is held by hand during the work to prevent the same from being disturbed on the sustaining claw. It has however been proposed to substitute for the action by hand the pressure of a rod slidable according to 25 the axis of rotation of the cutting tool and which bears on the center of the plate under the action of a spring or of a balance-weight.

According to this invention, the cutting 30 tool is provided with a slidable rod of this kind of which the end is diametrically slotted and with a cutting blade which passes freely through such slit and of which the front end is enabled to strike the whole of the surface of the button to be turned. By 35 means of this arrangement, the cutting blade which is enabled to work all the surface of the button is of a single piece and can on that account be easily mounted, taken out, sharpened and adjusted in position without 40 interfering with the operation of the slidable slotted pressure rod through which it passes.

The accompanying drawings show by way of example one embodiment of the improved machine according to this invention.

45 Figure 1 is a longitudinal section of an improved cutting tool. Fig. 1^a includes perspective views of the parts of the cutting tool detached. Fig. 2 is a cross section on the line A—A of Fig. 1. Fig. 3 is a side 50 view of a button of which the back face is turned. Fig. 4 is a cross section of a plate when being worked and of a claw against which the said plate is applied. Fig. 5 is a cross section of a claw, and of a button 55 having both faces turned, the button being shown separated from the plate. Fig. 6 is

a plan view of a lathe for the manufacture of buttons. Figs. 7 and 8 represent a vertical section and a side elevation of a lathe.

The blade 1, of which the front end 2 is 60 so cut and shaped as to make up the top of the buttons, is slipped into the interior of a carrier composed of a body part 3 and of a sleeve 4 secured together with a screw 5. The body 3 comprises a threaded part screwing into the shaft of the lathe and, at the opposite side, a hollow cylindrical part the outer diameter of which corresponds with the width of the blade 1, and in which are provided two slits 6 for receiving such blade. 70 The fastening of the latter is insured by means of two screws 7, screwed into the thickness of the sleeve 4 and pressing the blade 1 with their points against the edges of the slits 6. The position of the blade in 75 such carrier is so adjusted that it passes a little beyond the corresponding end 8 of the body part 3. The pressure rod 9 is slidable in the interior of such body part, and the front part of such rod is diametrically 80 slotted to receive the blade 1 and is enabled to pass a little beyond the latter as shown in the drawings.

In the lathe shown in Fig. 6, the shaft 11, on which is secured the tool carrier 3 and 85 which revolves in the bearings 13 and 14, is provided with an axial bore through which the rod 15 is slidable; the outer end of the latter is sustained against a cross-bar 16, which is carried by two rods 17 parallelly 90 guided in bearings 18 and drawn upon by the springs 19. Under the action of the springs 19, the rod 15 pushes the rod 9 outwardly as shown in Figs. 1 and 6. The advance of the rod 9 is limited by a nut 20 95 abutting against the tool carrier; it is adjusted each time the blade is sharpened. In front of the tool is located a claw 25 secured on a wedge shaped slide 26, which is guided in the standards 27 of the fixed support 28. 100 Such claw is surrounded by a ring 44 secured by means of a rigid support on one of the standards of the support. In axial line with the slide 26 is located a cylindrical rod 29 carrying a spline or key 30 on a part of 105 its length, and guided in a sleeve 31 which is rigidly secured in a bearing 32 integral with one of the standards 27. The outer end of the rod 29 is guided in another arm 33 of the support. Under the action of the spring 110 34, the slide 26 pushes the rod 29 in such a manner that the end of such spline or key 30

bears on a cam 35 which abuts against the arm 33 and which is free to turn around the rod 29. The cam 35 comprises a helical contour and a steep incline so that at each revolution of such cam, the rod 29 and the slide carrying the claw are gradually pushed in the direction of the arrow A (see Fig. 7) and then suddenly retracted by the spring 34. To obtain the rotation of the cam 35, use is made of a pulley 36 secured on the latter and surrounded by a leather strip 37 or other frictional part, and also of a pulley 38 free to revolve on an eccentric portion 39 of the sleeve 31, the inner face of such pulley 38 being adapted to frictionally engage the said leather strip and carry forward the pulley 36. The pulley 38 is given a continuous rotary motion for instance by means of a belt. It will be understood that if the leather strip 37 surrounds completely the pulley 36, there would be constantly contact between such strip 37 and the pulley 38 at the point invariable in this instance, where the circles are tangent, and the rotation of the pulley 36 and of the cam 35 would be continual. But Fig. 8 shows that the strip 27 on the pulley 36 presents an interruption of continuity at 40; the result is that if such strip is brought into contact with the pulley 38 in turning by hand the pulley 36 by means of a button 41, the carrying forward by friction would be produced until the said interruption of continuity 40 reaches the tangence point of the circles. With this device, all that need be done is to turn the pulley 36 slightly by means of the button 41 to put the same in gear with the driving pulley 38 and the putting out of gear is automatically produced when the revolution of the pulley 36 is finished. The machine thus constituted allows of any of the faces of the button being made up and if desired of the stud or button of the outer washer being detached. For instance, the operator takes a corozo plate 42 and applies the same against the claw 25 (see Fig. 1), then puts the pulley 36 in gear so as to make the said claw advance toward the tool, which revolves continually. Before meeting with the tool, the plate 42 strikes the rod 9 and pushes the same in compressing the springs 19, so that the said plate is pressed against the claw and can be released at once by the operator; the latter therefore can immediately make ready for introducing a fresh plate. The advance being continued, the plate 42 lies attacked and hollowed by the tool as shown at 43 (see Fig. 4), then the claw 25 recedes suddenly; the plate is then pushed from the operator by the rod 9 and falls. If the plate comes back at the same time as the claw and has a tendency to adhere thereto, it is detached by the fixed ring 44 which stops the same (see Fig. 7). Afterward the opposite face of the plate will be made up after hav-

ing changed the tool and the claw, and the latter must be so shaped as to center the button; such second tool will detach the button completely from the washer.

Claims:

1. In a machine for the manufacture of buttons, the combination of a rotary tool carrier having a chamber therein and an axial perforation, a cutting blade slipped into the said chamber and secured in a diametral position in the said chamber, and a rod slidable through the perforation of the tool carrier and having two branches which extend into the said chamber on both faces of the cutting tool at the middle portion thereof, the ends of the said branches being adapted to extend beyond the cutting edge of the blade. 70

2. In a machine for the manufacture of buttons, the combination of a rotary tool carrier in the form of a socket and having diametrically opposite grooves, a cutting blade the longitudinal edges of which are slipped into the said grooves, a rod slidable through the tool carrier and having a slit to receive the cutting blade, and means whereby to push such rod in such a manner that its slotted end comes a little beyond the cutting blade. 85

3. In a machine for the manufacture of buttons, the combination of a socket having on one side a threaded part and on the other side a diametrically slotted cylindrical part, a sleeve surrounding such slotted cylindrical part, a cutting blade of which the edges are slipped into the slits of the socket, means whereby to secure the sleeve on the socket and to secure the blade in the socket, and a slotted rod which slides in the socket, the branches of such rod extending on both sides 95 of the blade and beyond the latter. 100

4. In a machine for the manufacture of buttons, the combination of a rotary tool holder or carrier, a cutting blade secured in such tool holder in a diametral position, a slotted rod slidable in the tool carrier and having its branches extended on both sides of the blade at the middle portion thereof, means whereby to push such rod in such a manner that its slotted end extends beyond the blade, a non rotary sustaining claw located in front of the tool holder and of the cutting blade, and means for advancing such claw toward the tool carrier and the blade and to retract the same. 110

5. In a machine for the manufacture of buttons, the combination of a rotary tool carrier having a chamber therein and formed with diametrically opposite grooves, and an axial perforation, a cutting blade extending into said chamber and having its longitudinal edges engaging the said grooves, the front or outer end of said blade forming a cutting edge, adapted to act on the entire surface of the button to be turned, 125 130

means for securing the blade in position in the said grooves, a rod slidable through the axial perforation of the tool carrier, the said rod being slotted longitudinally at its front 5 part to receive the said cutting blade, the two branches formed by said slit, extending on opposite sides of the blade at the middle portion thereof, the ends of said branches being adapted to extend outward beyond the 10 cutting edge of said blade, and spring con-

trolled means connected with said rod for normally holding the same in said outward position.

In testimony, that I claim the foregoing as my invention I have signed my name in 15 presence of two subscribing witnesses.

EMILE GAUDION.
